UNITED STATES PATENT OFFICE.

OLIVER L. DOSCH, OF ELIZABETH, NEW JERSEY, ASSIGNOR TO THE SINGER MANUFACTURING COMPANY, A CORPORATION OF NEW JERSEY.

FOUNDRY SYSTEM.

1,276,039.

Specification of Letters Patent. Patented Aug. 20, 1918.

Application filed December 8, 1916. Serial No. 135,752.

To all whom it may concern:

Be it known that I, OLIVER L. DOSCH, a citizen of the United States, residing at Elizabeth, in the county of Union and State 5 of New Jersey, have invented certain new and useful Improvements in Foundry Systems, of which the following is a specification, reference being had therein to the accompanying drawings.

10 This invention relates to so-called "continuous" foundry systems, wherein the molds are formed at a molding station and placed upon an endless conveyer which first transports them to a pouring station, usually adjacent the cupola, and thence to a shake-out station where the poured molds are removed from the conveyer and broken up to release the castings; and wherein the used sand from the shake-out station is retempered and returned to the molding station.

15 While the use of a continuous system is often desirable because of the economies resulting from increased production, specialization of labor, reduction of ground-floor space, &c., it is not feasible to utilize any of the continuous systems heretofore known for the production of high grade castings for the reason, very largely, that none is arranged and equipped to efficiently, economically and properly retemper the used sand prior to its return to the molding station. Certain of these systems tumble the sand 20 too much, causing it to "ball" or form into little pellets; others treat the sand continuously in various mixing and tempering machines, as it is shaken from the molds, with the result that the same quantity of water is applied during a certain specified period of time, whether the sand goes through in

25 large quantities or small quantities, whether it is largely composed of old sand or largely composed of new sand, and whether the molds which it formed contained castings of large size or small size, in which cases the sand would be either too dry or too wet. It

30 is well known by those familiar with foundry practice that to secure a uniform grade of work it is essential that the sand be tempered evenly, and especially for the work in hand; that is if the sand is too wet for one mold and too dry for another, the castings will not only be different in surface quality or finish, but will vary in hardness. If castings which are small and require machining are made in sand which is not prop-

erly tempered, some will be so hard that it will be impossible to machine them.

One of the main objects of this invention is to so reorganize and arrange the components parts of a continuous foundry system that the used sand may be retempered and returned to the molding station in a simple, expeditious and economical manner, and in correct condition for high-class molding.

Another object of the invention is to provide a continuous foundry system capable of simultaneously handling two entirely different classes of work, each requiring sand of a particular grade or consistency, and in which each grade of sand may be tempered and returned to the molding station in correct condition independently of and without mixture with the other grade.

Another object of the invention is to provide means for supplying the molders with facing sand in an efficient and economical manner and without unduly obstructing the floor space at the molding station.

Further objects of the invention are to provide an improved method of handling molds and their accessories in continuous foundry practice whereby a minimum amount of power will be required to operate the system, and to provide an improved method of handling the used sand whereby the "balling" tendency of the sand may be overcome, and whereby it may be thoroughly homogenized, re-vitalized, re-tempered and returned to the molding station, in an economical manner and in the correct condition for high grade molding.

Further objects of the invention are the elimination of certain undesirable features characteristic of prior continuous systems; such as, the necessity of pouring the molds while occupying positions above unpoured molds, and the frequent starting and stopping of the conveyer with its heavy load of poured and unpoured molds.

The foundry system hereinafter described embodies the several principles of my invention in the best form which I have thus far seen fit to devise, but in presenting these several features specifically I do not intend thereby to limit the scope of my invention.

With the above and other objects in view, as will be more fully described hereinafter, the invention comprises, in its preferred embodiment, an endless conveyer of rec-

tangular form having a lower horizontal run whereon the molds are placed and poured, an ascending run whereon the poured molds are elevated to an upper level, an upper 5 horizontal run from which the molds are removed and shaken out and upon which the castings and mold accessories are replaced, and a descending run whereon the castings and mold accessories are lowered 10 to the molding floor. The conveyer includes an endless link-belt to which are pivotally connected the component mold carriers or trays of a series. In the present instance means are provided for restraining 15 the trays against tilting or swinging while they are passing along the lower and upper horizontal runs. Series of molding machines are arranged along opposite sides of the lower horizontal run, so that the 20 molds may be formed in sufficient numbers to keep the trays filled, and movable pouring platforms are arranged at opposite sides of the end-portion of the horizontal run which joins the ascending run, so that the 25 molds may be poured while on a horizontal run and so that the positions of the pourers relatively to the molds may remain fixed during the pouring operation, as in ordinary floor pouring.

30 Shake-out boxes or hoppers disposed at opposite sides of the upper horizontal run of the conveyer, serve to conduct the used sand to suitable riddles or screening devices placed directly beneath their discharge orifices. An exhaust fan connected to these 35 hoppers acts to draw air downwardly into their mouths and carry away the heated gases, steam and dust, which otherwise would tend to rise and inconvenience the 40 workmen stationed at this point. From the fan the exhaust-matter is discharged into a moderately large settling chamber wherein the fine particles of sand are deposited. An air-discharging vent leads 45 from the settling chamber through the roof of the building.

The sand passing through each riddle is evenly distributed upon a corresponding endless belt conveyer from which it is 50 caused to fall to a sand tempering or homogenizing floor by a specially designed plow adapted to travel constantly back-and-forth along said belt at a relatively slow speed. The purpose of this plow is to scrape the 55 sand from the belt in a thin layer, causing it to fall to the floor in the form of a thin sheet, thus exposing every particle of the sand to the cooling action of the air and effecting the liberation of most of the hot 60 gases. These sand-belts are parallel and are spaced apart so that the sand which falls to the tempering floor will form separate and distinct parallel ridges along the length of the latter. The tempering floor 65 is equipped with one or more hose connec-

tions for supplying different portions of each sand-ridge with varying amounts of water to give the entire mass of sand the temper desired for the class of work in hand.

A screw-conveyer is journaled to rotate in a traveling frame which is provided with wheels enabling it to run along suitable track-ways which extend lengthwise of the tempering floor and parallel with the sand-ridges deposited thereon. Suitable manually controlled motors carried by the frame are independently connected to drive the latter and rotate the conveyer about the axis extending crosswise of the tempering 75 floor. The purpose of this conveyer is to scrape the sand outwardly across the tempering floor and into a series of storage bins disposed lengthwise of said floor and carrying sand-valves at their lower ends 80 adapted to deliver the tempered sand in measured quantities to the molding machines on the molding floor. The screw-conveyer may be run over the floor at manually controlled intervals to repeatedly 85 move the sand toward the sand-bins and permit it to rest intermittently.

In the accompanying drawings, Figure 1 is a side elevation, partly in section, of the building structure showing the various 90 working parts in their proper relative positions. Fig. 2 is a transverse cross-sectional view of the building looking toward the left, Fig. 1. Fig. 3 is a plan view of the lower floor showing the layout of the molding and pouring stations. Fig. 4 is a plan view of the equipment at the intermediate floor showing also a portion of the upper floor. Figs. 5, 6 and 7 are detail views of the moving platform at the pouring station. Fig. 8 is a side elevation of one of the 95 sand-valves through which the sand may be delivered in measured quantities to the molding machines. Fig. 9 is a cross-section of the mechanism at one side of the shake-out station for screening the sand and depositing it upon the belt-conveyer. Fig. 10 is a plan view showing details of construction of the sand-screening and conveying mechanism. Fig. 11 is a transverse cross-section on line 11—11, Fig. 12. Fig. 12 is a side elevation of the parts shown in Fig. 10. Fig. 13 is a perspective view of one of the plows used for scraping the sand from the sand-belts. Figs. 14, 15, 16 and 17 are 100 views showing details of construction of the mold-conveyer and carriers. Fig. 18 is a plan view of the transfer-device for the traveling screw-conveyer showing the latter in position for transfer. Fig. 19 is a side 105 elevation, Fig. 20 an end elevation and Fig. 21 is a reverse end-elevation of the parts shown in Fig. 18.

In the preferred embodiment of the invention, as illustrated, the various working 110

parts are sustained by an elongated building structure or frame-work including a lower or molding floor A, an intermediate sand tempering or homogenizing floor B, an 5 upper or shake-out floor C, and a suitable roof D. Disposed substantially in a vertical plane, centrally of the width of the building structure, is an endless mold-conveyer traveling in a rectangular path comprising 10 a lower horizontal run 1, Fig. 1, a vertically ascending run 2, an upper horizontal run 3, and a vertically descending run 4. The lower and upper runs of the mold-conveyer extending lengthwise of the 15 lower and upper floors, respectively, while the ascending and descending runs extend through vertical shafts 5 and 6, respectively, located at the opposite ends of the building.

Referring to Figs. 14 to 17 inclusive, the 20 mold-conveyer comprises two parallel endless chains or link-belts 7-7 each of which includes a series of alternately inwardly and outwardly disposed pairs of spaced links 8-8 whose end-portions are connected 25 in overlapping relation by bolts 9 upon which are journaled the rollers 10. Depending from the conveyer-chains at intervals along the length of the latter, are a series of mold-carriers, indicated generally at 30 11, each of which comprises a hollow transverse beam 12 to the center of which is bolted the upper flanged end of a depending tubular member 13 which carries at its lower end a flat, horizontally disposed, mold- 35 carrying tray 14.

Fixedly secured to and projecting from the opposite ends of the beam 12 are pivot-pins 15, each of which enters suitable bearing apertures formed midway between the 40 ends of a corresponding pair of links 8. The portion of each pin 15 extending between a pair of links is surrounded by a sleeve 16 and the free ends of said pins are threaded to receive nuts 17. Each of the 45 beams 12, together with its complement of pins 15, sleeves 16 and nuts 17, serves as a tie-rod to maintain the chains 7, 7 in proper laterally spaced relation. A pair of flanged supporting wheels 18 are mounted to turn 50 on bearing pins 19 which are fixedly secured in position between the adjacent apertured ends of a pair of spaced cross-bars 20 formed at each end of the beam 12. Bolted to the standard 13 of each carrier are a pair of 55 oppositely extending brackets 21 which may be utilized to carry certain of the mold accessories from the shake-out floor to the molding floor.

The wheels 18, which support the mold- 60 carriers 11 while traveling at the lower and upper levels, run on the parallel overhead rails 22, 22, each of which is carried by the inwardly directed free end-portions of a series of depending L-shaped hangers 23 whose 65 upper ends are bolted to longitudinally ex-

tending beams 24, 24, supported in any suitable manner. At the horizontal runs the chains 7, 7 merely serve to pull the mold-carriers and are supported entirely by the pins 15. Since each of the depending mold-carriers runs on four wheels during its travel along the lower and upper runs, it will be seen that said carriers are very stable and that swinging or tilting movements of the trays 14 are prevented. 75

While traveling along the vertical run the mold-carriers 11 are suspended entirely from the chains 7, 7 and are free to swing about the pivot pins 15, as shown in Fig. 14. Mounted within each of the similar shafts 80 5, 6 surrounding the vertical runs, are two pairs of opposed vertical rails 25, 26, Fig. 16, which form guidewalls for the rollers 10 of the chains 7, 7. At the ascending run 2 the lower and upper end-portions of these 85 guide rails are curved on arcs of concentric circles and terminate in short flared extensions 27, 27. At the receiving end of the ascending run 2 the rollers 10 enter between the extensions 27, 27 and are gradually drawn 90 into rolling contact with the then upper rail 26. Near the discharging end of the ascending run 2 the rollers 10 bear against a similarly curved portion of the rail 26. Just before the rollers 10 leave the rails 25, 26, the 95 carrier-wheels 18 ride upon the horizontal rails 22 at the upper run 3 and again resume their supporting function.

At the end of the upper horizontal run 3 the chains 7, 7 run over the driving sprockets 28, 28 which are mounted upon the shaft 29 journaled in the framework 30 supported by the upper floor. A suitable motor M is belted to a countershaft 31 which, in turn, is belt-connected to a series of speed-reducing gears 32, 32 connected to the sprocket-shaft 29. From the sprocket-wheels the rollers 10 pass between the spaced pairs of guide-rails sustained within the shaft 6 and are guided during their descent to the lower end of said shaft where they roll about the lower convexly curved portions of the rail 26 and leave the latter shortly after the carrier-wheels 18 ride onto the lower horizontal rails 22. 100 105 110 115

At the molding station E, Figs. 1 and 3, at each side of the lower horizontal run of the conveyer, is a series of molding machines 33 of well known construction, wherein the molds may be rapidly formed in a manner familiar to those skilled in the art. Disposed directly above each series of the molding machines is a series of sand-bins 34 whose upper or receiving ends 35 are widened out and form a practically continuous sand receiving slot extending along the outer edge-portion of the sand-tempering floor B, Fig. 4. At its lower discharge orifice each of the sand-bins carries a pair of sand-valves 36 which are disposed directly 120 125 130

above a corresponding one of the molding machines 33 and are adapted to measure out the correct quantity of sand for the mold and allow it to fall directly onto the pattern and flask parts supported by the machine. Referring to Fig. 8 it will be seen that each of the sand-valves comprises a hollow cylindrical drum 37 axially of which is journaled a shaft 38 to which is secured 5 four curved radially disposed vanes 39 dividing the drum into four equal compartments. The upper side of the drum is connected with a chute leading from a sand-bin and the lower side of said drum is formed 10 with a discharge orifice 40. Secured to the shaft 38 is a disk 41 having four peripheral notches affording shoulders or ratchet-teeth 42 adapted to be acted upon by the pawl 43 carried by a lever 44 fulcrumed on the shaft 15 38 and connected at its free end to a piston-rod 45 carrying the piston 46 disposed within the pneumatic cylinder 47. Suitable air-hose connections 48, at the opposite ends of the cylinder 47, permit the lever 44 to be 20 controlled pneumatically to advance the vanes 39 a quarter of a revolution and thereby carry a measured quantity of sand to the lower side of the drum 37 from which it falls through the orifice 40 onto the molding machine below.

For high grade castings it is desirable to apply a thin layer of extra fine or facing sand to the pattern before the mold is filled with the coarser molding sand. To this 25 end a series of stands 49 are placed in a row in alternating arrangement with the molding machines 33 so that an intermediate stand may be easily reached by operators of each of the two adjacent molding machines. 30 The facing sand is supplied to the stands 49 through suitable chutes 50 which extend upwardly through the sand-bins and terminate at the level of the sand tempering floor B. Suitable covers 51 are placed over the upper 35 ends of the chutes 50 to prevent the entrance of coarser sand during the operation of the traveling screw-conveyer, to be hereinafter described. The facing sand is prepared in the usual pug-mill 52 and centrifugal mixer 40 52', which are placed at one end of the sand tempering floor B, and is in the present instance manually conveyed to and deposited within the chutes 50.

After the molds have been formed and 45 placed upon the mold-carriers 11 they are conveyed to the pouring station F, Fig. 1. The floor of the pouring station is raised slightly, in order that the pourers may not have to elevate the heavy ladles to an 50 ordinate height, and is formed with a pit 53 within which is disposed the mechanism for supporting and driving a pair of moving platforms 54, 54 arranged one at each 55 side of the central vertical plane of the mold-conveyer. As these platforms are pre-

cisely similar, a description of one will suffice. Referring to Figs. 3, 5, 6 and 7, the platforms 54 comprise a series of similar rectangular sections or gratings 55, formed at their four corners with downwardly extending ears 56 apertured to receive the cross-shafts 57 which pivotally connect adjacent gratings. A pair of link belts 59, 59, each comprising spaced pairs of alternately inwardly and outwardly disposed overlapping links, connect the oppositely extending free end-portions of the cross-shafts 57. Flanged wheels 60^x are mounted upon the shafts 57 connecting the links of the belts 59 and are adapted to run on the rails 60 supported by suitable cross-beams 61 sustained within the pit 53. A pair of idler sprocket-wheels 62 for the link-belts 59 is disposed at one end of the rails 60 and serve to carry the gratings from the lower to the upper level of the moving platform. A pair of driving sprocket-wheels 63, disposed at the other end of the rails 60, are fixed to a driving shaft 63' which is slowly rotated by means of suitable gearing 64 driven by a 90 motor, not shown. The ratios of the gearing and speed of the motor are so chosen that the moving platform travels at substantially the same speed as the mold-carriers 11. The pouring equipment further comprises hand 95 ladles such as 66, which may be filled with molten metal from the trucks 67.

The poured molds, while cooling, travel slowly up the ascending run 2 and along the upper run 3 to the shake-out station G. 100 Operators stationed at this point remove the molds from the conveyer and dump them upon gratings 68, Figs. 2 and 12, supported at the mouths of the shake-out boxes or hoppers 69 which are disposed one at 105 each side of the conveyer. The gratings permit the sand to fall into the hoppers 69 but retain the castings which are to be replaced upon the conveyer together with the mold accessories or flask parts.

Referring to Figs. 2, 9 and 12, it will be seen that each of the shake-out hoppers 69 includes a lower section 70 which tapers downwardly to a constricted discharge orifice 71 disposed above a sand-riddle or 115 screening device 72. Projecting into each of the hoppers 69 through a side orifice 73 below the mouth thereof, is the lower end of an exhaust conduit 74 whose upper end is connected to a horizontal conduit 75 leading to the exhaust-fan 76 which discharges into the settling chamber 77. The suction created by the fan 76 causes air currents to flow downwardly into the mouths of the hoppers 69 and thence through the conduits 120 74, 75, into the settling chamber 77. These air currents carry away the obnoxious steam, dust and heated gases freed by the falling sand. Some of the finer particles of sand are also sucked into the conduits 74. When 130

the exhaust-matter enters the settling chamber its velocity drops considerably and the fine particles of sand which are heavier than air settle to the floor and may be recovered.

5 An exhaust vent 78 connects the settling chamber with the outside air. The fan 76 may conveniently be driven from the countershaft 31 by a belt 78.

In order that mixture of the sands used 10 at each side of the system may be avoided two separate mechanisms are provided, one at each side of the central vertical plane of the mold-conveyer, for screening the used sand and depositing it along the length of 15 the sand-tempering floor in the form of two separate and distinct ridges. As these mechanisms are of similar construction the description will be restricted to the mechanism at one side of the system.

20 The sand riddle 72, Figs. 10 and 12, comprises a rectangular frame-work which supports the screen 79. Two side-pieces 80, 80, and one end-piece 81 prevent spilling of the sand over the edges of the screen 79. The 25 riddle is suspended at its four corners from the studding at the under side of the upper floor C by four flat springs 82 and is inclined to the horizontal, as shown in Fig. 12. Vibratory movements are imparted to

30 the riddle by means of the eccentrics 83, 83, which are connected through the links 84, 84, to the opposite ends of the cross-bar 85 extending transversely of and secured beneath the frame-work of the riddle. The 35 eccentrics 83 are mounted on the shaft 86 which is driven from the countershaft 31 by a belt 87. The sand in falling through the hopper 69 onto the riddle 72 usually breaks up into its original condition of fine-

40 ness and passes through the screen 79. Any pieces of iron or hardened lumps of sand which remain on the screen find their way to the lower end thereof and fall into the chute 88 which leads to a scrap heap. Dis-

45 posed below the riddle 72 is a second hopper 89 having its reduced lower discharge orifice 90 disposed very close to the upper surface of a horizontally disposed conveyer-belt 91. The front side wall 92 of the hop-

50 per 89, Fig. 9, is fitted with a sliding gate 93 and operating handle 94 to regulate the thickness of the layer of sand carried away by the belt 91 as it passes from under the orifice 90. The belt 91 is carried on a series

55 of rollers 95 journaled in brackets 96, Fig. 13, secured to suitable cross-beams 97 supported by the longitudinally extending beams 98. At its opposite ends the belt runs over the driving pulley 99 and the idler pulley 100, respectively. The driving pulley 99 is secured to the shaft 101 which carries the gear-wheel 102 meshing with the pinion 103 on the countershaft 104 which is driven by the belt 105 from the coun-

60 tershaft 86. Referring to Figs. 1 and 2 it

will be seen that the conveyer-belt extends lengthwise of the intermediate floor B and is supported some distance above the latter.

In order that the sand, which is carried away from the shake-out station by the belt-conveyer, may be deposited in the form of a ridge extending lengthwise of the floor B, a traveling plow or scraper is arranged to move slowly back-and-forth along the length of the upper or loaded side of the belt 91. As shown best in Fig. 13, this plow comprises a rectangular frame-work 106 supported at its four corners by wheels 107 running on the track 108 and fitted with a diagonally extending scraper-blade 109. A belt-supporting platform 110 is hung from the frame-work 106 by means of straps 111 and the upper surface of said platform is spaced below the lower edge of the blade 109 a distance slightly greater than the thickness of the belt 91. The platform 110 serves to hold the loaded belt 91 close to the blade 109. Without this platform the belt would sag between the rollers 95 and would not be scraped clean by said blade. A diagonally disposed brush 112 is supported at the rear of the blade 109 by suitable bars 113 secured to the frame-work 106 and serves to brush off any sand which may escape the action of said blade.

Extending above and longitudinally of the path of movement of the plow are three parallel spaced beams 114 to the lower surfaces of which are secured three flat metal strips 115 which are somewhat wider than the beams 114 and define two parallel slots 116 between them. These spaced metal strips are adapted to support the two parallel runs of an endless chain 117 which is suspended at intervals from a series of short cross-pieces 118 adapted to bridge the slots 116 and slide along the strips 115. The chain 117, Figs. 10 and 12, runs around the idler-sprocket 119 and driving sprocket 120 which latter is carried by a vertical shaft 121 connected by beveled gears 122 with a countershaft 123 which is driven through the spur-gears 124 and worm-gearing 125 by a countershaft 126 carrying the stepped pulley 127 which is belt-connected to a reversely stepped pulley 128 secured to the countershaft 86. A coupling bar 129, Fig. 13, pivoted to the frame-work 106 at 130 and pivotally connected to the chain 117 by a depending pin 131 serves to transmit the slow motion of the chain to the plow. During the travel of the pin 131 about either one of the sprockets 119, 120, the coupling bar 129 merely swings about the pivot 130 as the motion of the plow reverses.

It is obvious that as the sand upon the belt 91 strikes the diagonal blade 109 it will be deflected to one side and will fall over the edge of the belt in the form of a thin sheet to the floor B. The sand will thus be

aerated and cooled in very much the same manner as when tossed in a spray from one heap to another in the well known process of hand tempering with a shovel commonly employed on the foundry floor. After the sand has been deposited in a ridge on the intermediate floor, a skilled workman sprays different portions of said ridge with varying quantities of water from the hose *h*; the 5 quantity of water supplied depending upon the observed condition of the sand and the temper desired for the class of work in hand, 10

The sand after lying in this condition for a sufficient length of time to complete the 15 cooling process and allow the water to soak into and permeate the sand mass, is moved outwardly across the floor and into the open slot formed by the contiguous mouths of the sand-bins 34 by a screw-conveyer, Figs. 18, 20 19 and 20, comprising a spiral blade 132 secured to a shaft 133 whose reduced extremities are journaled in bearings 134 sustained by the depending hanger members 135 carried by the traveling frame 136 provided 25 with flanged supporting wheels 137 which are adapted to run on either of the parallel track-ways 138, 139, extending lengthwise of the intermediate floor B. The shaft 133 extends crosswise of the floor and 30 is supported so that the free edge portion of the spiral blade 132 just clears said floor. At its outer end the shaft 133 carries the sprocket 140 which is connected by a chain 141 to a driving sprocket 142 secured to a 35 countershaft 143 which is connected by spur gears 144 to a suitable motor 145, the direction of rotation and speed of which may be controlled by the usual controller 146.

The supporting frame 136 of the screw-conveyer may be propelled along the track-ways 138 and 139 by means of a second independently controlled motor 147 which is connected by suitable speed-reducing spur-gears 148 to a countershaft 149 carrying a worm 45 150 meshing with a worm-wheel 151 secured to a countershaft 152 carrying a sprocket 153 which is connected by a chain 154 to a second sprocket 155 secured to the shaft 156 which is journaled lengthwise of the frame 50 136 and carries at its opposite ends a pair of the supporting wheels 137. The electric current for operating the motors 145, 147, may be supplied through two parallel trolley wires one of which is shown at 157, Fig. 55 1. Either of the two trolley poles 158, 158, each carrying conductors, not shown, serves to connect the trolley wires 157 to the motor circuits in the usual manner.

In the present instance, a transfer device 60 T is installed at one end of the tracks 138, 139, in order that the single screw-conveyer shown may be shifted from one to the other side of the tempering floor. This transfer device may comprise a horizontally disposed 65 rectangular upper frame-work 160 to one

end of which is secured a bearing ring 161 surrounding the fixed pivot post 162 and supported by the stepped collar 163 which is bolted to the pivot post 162 at 164. A channel iron 165 extends transversely of and beneath the frame-work 160 at a point remote 70 from the pivot post 162 and is suspended at its opposite ends from a semi-circular I-beam 166 by means of a pair of rods 167 depending from the trolley trucks 168. The I-beam 75 166 is secured to the under side of a suitably constructed frame-work 169, Figs. 4 and 19.

Depending from the end of the frame 160 adjacent the post 162 is a vertically disposed end frame-work 170 formed with a 80 rail-supporting ledge 171 and carrying at its lower end a guide-ring 172 which surrounds the post 162. Depending from the opposite end of the upper frame-work 160 is an outer end frame-work 174 carrying at 85 its lower edge an inwardly projecting rail-supporting ledge 175. Supported by the ledges 171 and 175 are two short rails 176, 176, which are adapted to register with the track-ways 138, 138, or 139, 139, as shown 90 best in Fig. 18. The screw-conveyer may thus be run onto the transfer device T and readily swung around from one to the other of the adjacent track-ways.

In the operation of the above described 95 system, the mold-conveyer is driven at a uniform slow speed by the sprockets 28, 28. The molds are formed in the various molding machines 33, in the usual manner, and are carried to and carefully deposited upon 100 the trays 14 of the mold-carriers 11. As the molds are usually quite heavy the workmen may frequently find it convenient to steady themselves by leaning against the carriers 11 while placing the molds thereon. 105 If the carriers were free to swing it would be a difficult matter to place a heavy mold thereon without subjecting it to destructive jarring. As the carriers 11 of the present construction are rigidly held in a horizontal 110 plane, while traveling along the horizontal runs, this difficulty is overcome. As is natural, the molds formed at one side of the system are deposited upon the same side of the mold-conveyer. 115

As the filled trays 14 slowly pass the pouring station F the ladlers, standing upon the moving platform 54, pour the molds from hand ladles which may be refilled with molten metal from the trucks or buggy 120 ladles 67. Since the platforms 54 travel at the same speed as the rigidly supported mold-carriers the positions of the pourers relative to the mold-carriers remain fixed. The molds may therefore be poured with the 125 same ease and precision as when resting upon the floor. If the carriers were free to swing while passing the pouring station the pouring operation would become extremely difficult and uncertain. Much metal 130

would be spilled as the pourers attempted to direct the streams of molten metal from the ladles into the sprue holes of the swinging molds. With the present arrangement, a 5 pourer, if he so desires, may place one foot upon the tray 14 and steady the heavy ladle by resting the handle thereof upon his knee.

While the poured molds are traveling up the ascending run 2 and along the upper 10 horizontal run 3 the metal cools sufficiently to solidify. When the molds reach the shake-out station G they are removed from the conveyer by workmen stationed at this point and dumped onto the gratings 68 of 15 the shake-out hoppers 69. The sand falls through the gratings leaving the flask parts and castings behind to be replaced upon the conveyer for transit to the lower floor. As is natural, the molds at one side of the conveyer are dumped onto the grating 68 at 20 the same side. There is, therefore, no tendency for the sand used at one side of the system to be diverted to the other side at this point. While the castings and mold accessories, usual in foundry practice, are 25 traveling down the descending run 4 of the mold-conveyer, they form a counterpoise for the like parts traveling up the ascending run at the opposite end of the building. As a 30 result, the driving motor M is drawn upon to supply merely enough power to overcome the friction of the system and elevate the sand in the molds from the lower to the upper floor.

35 Having thus set forth the nature of the invention, what I claim herein is:—

1. In a foundry machine, an endless carrier having a horizontal run whereon the molds are placed and poured, a vertical upward run whereon they are elevated to a 40 higher floor, a second horizontal run whereon the molds are removed and shaken out, and a vertical downward run whereon the flasks and castings are lowered, forming a 45 counterpoise to the flasks and castings on the vertical upward run.

2. In a foundry system, in combination, a molding floor, a series of molding machines and a pouring equipment on said 50 molding floor, an endless conveyer having four runs substantially in the same vertical plane, the lower horizontal run being adjacent to said series of molding machines and the pouring equipment, an upper floor 55 at the upper horizontal run, a shake-out equipment at said upper floor, a sand tempering floor whereon the sand and water are homogenized, a conveyer whereby the shaken out sand is distributed on the sand 60 tempering floor, means for wetting the sand, a device adapted to act successively to move different parts of the distributed mixture, and means whereby said mixture is delivered from the sand tempering floor to 65 the molding floor below.

3. In a foundry system, in combination, a lower floor, an upper floor, a series of molding machines and a pouring equipment, a conveyer having a lower horizontal run adjacent the series of molding machines and 70 the pouring equipment, and an upper horizontal run, a shake-out equipment at the upper run, an intermediate floor whereon the sand and water are homogenized, a conveyer whereby the shaken-out sand is distributed 75 on the intermediate floor, means for wetting the sand, means whereby the sand is delivered from the intermediate to the lower floor, and a traveling screw-conveyer adapted to act successively on different parts 80 of the sand distributed along the intermediate floor to transfer it to said delivering means.

4. In a foundry system, in combination, a lower, an upper and an intermediate floor, 85 a series of molding machines and a pouring equipment at the lower floor, an endless mold conveyer having a lower horizontal run at the lower floor adjacent the molding machines and pouring equipment, a vertical 90 upward run leading to the upper floor, a horizontal run at the upper floor, and a vertical downward run leading to the lower floor, a shake-out equipment at the upper floor, means for conveying the sand away 95 from the shake-out equipment and depositing it along the intermediate floor, a sand tempering equipment at the intermediate floor, and means for conveying the tempered sand to the molding machines. 100

5. In a foundry machine, an endless carrier having a base portion traveling horizontally and upon which the molds are placed and poured, a vertical upward run whereon they are elevated to a higher floor, 105 a second horizontal run from which the molds are removed and shaken out, and a vertical downward run whereon the castings and mold accessories are lowered and form a counterpoise for the corresponding 110 parts of the filled molds in their upward travel.

6. In a continuous foundry system, in combination, lower and upper floors, an endless conveyer traveling in a rectangular path 115 and including lower and upper horizontal runs disposed at said lower and upper floors, respectively, mold-forming equipment at the lower floor beside the lower run, pouring equipment at the lower floor between 120 the mold-forming equipment and the ascending run, shake-out equipment at the upper floor beside the upper horizontal run, and means for driving said conveyer continuously. 125

7. In a continuous foundry system, in combination, lower and upper floors, an endless conveyer traveling in a rectangular path and including lower and upper horizontal runs disposed at said lower and upper floors, 130

- respectively, and further including ascending and descending runs, mold-forming equipment at the lower floor adjacent the lower horizontal run, pouring equipment at 5 the lower floor between the mold-forming equipment and the ascending run, and shake-out equipment at the upper floor adjacent that end-portion of the upper horizontal run which joins the descending run.
- 10 8. In a continuous foundry system, in combination, lower and upper floors, an endless conveyer traveling in a rectangular path and including lower and upper horizontal runs disposed at said lower and upper floors, 15 respectively, and further including ascending and descending runs, mold-forming equipment at the lower floor adjacent the lower horizontal run, pouring equipment at the lower floor adjacent that end-portion of 20 the lower horizontal run which joins the ascending run, shake-out equipment at the upper floor adjacent that end-portion of the upper horizontal run which joins the descending run, a sand tempering floor between said lower and upper floors and between said ascending and descending runs, means for distributing the sand from the 25 shake-out equipment along the sand tempering floor, and means whereby the tempered sand may be delivered to the lower floor.
9. In a foundry system, in combination, a lower floor, an upper floor, mold-forming and pouring equipments on the lower floor, an endless conveyer having a lower horizontal run adjacent the mold-forming and pouring equipments, an upward run leading to the upper floor, an upper horizontal run, and a vertical downward run, said conveyer including a series of suspended mold-carriers and means for restraining said carriers against swinging while passing through a portion of its horizontal travel.
10. In a foundry system, in combination, a lower floor, an upper floor, mold-forming and pouring equipments on the lower floor, an endless conveyer having a lower horizontal run adjacent the mold-forming and pouring equipments, an upward run leading to the upper floor, an upper horizontal run, and a vertical downward run, said conveyer including a series of suspended mold-carriers, and means for restraining said carriers against swinging while passing the mold-forming and pouring equipments.
11. In a foundry system, in combination, a lower floor, an upper floor, mold-forming and pouring equipments on the lower floor, an endless conveyer including suspended carriers and having a lower horizontal run adjacent the mold-forming and pouring equipments, said conveyer also having ascending and descending runs leading to and from said upper floor, said pouring equipment including a moving platform parallel- 65 ing a portion of the horizontal run, and

means for maintaining the suspended carriers in fixed angular relation with said platform while passing the latter.

12. In a foundry system, in combination, a building frame-work including lower, intermediate and upper floors, an endless conveyer disposed in a vertical plane and having horizontal runs at the lower and upper floors, a series of molding machines and a pouring equipment at the lower floor, a shake-out equipment at the upper floor, a sand tempering equipment at the intermediate floor, means for conducting the tempered sand to the molding machines, means on said intermediate floor for preparing facing sand, and chutes for conducting the preparing facing sand from the intermediate floor to readily accessible positions between adjacent molding machines. 70 75 80

13. In a foundry system, in combination, a lower molding floor, an endless conveyer disposed in a vertical plane and having a horizontal run at said lower floor, a series of molding machines disposed in a row along said floor, a sand tempering floor above said molding floor, means for preparing molding and facing sands on said sand tempering floor, a series of chutes for conducting the molding sand from the tempering floor to positions directly above their respective molding machines, and a second series of chutes arranged in alternation with the chutes of the first mentioned series for conducting the facing sand to readily accessible stations between adjacent molding machines. 85 90 95 100

14. A duplex foundry system comprising, in combination, an endless conveyer disposed substantially in a vertical plane, said conveyer having a lower horizontal run whereon the molds are placed and poured and a complement of mold-forming, pouring, shake-out and sand tempering equipments at each side of said vertical plane and adjacent said conveyer. 105 110

15. In a duplex foundry system, in combination, a frame-work including lower, upper and intermediate floors, an endless mold-conveyer having a horizontal run at the lower floor, a vertical upward run, a horizontal run at the upper floor and a vertical downward run, a mold-forming equipment at each side of said conveyer on the first floor, a pouring equipment on the first floor, two shake-out equipments at the third floor, one at each side of the conveyer, two sand conveyers one at each side of the vertical plane of said mold-conveyer for conveying sand from the shake-out equipments and distributing it along said intermediate floor, a sand tempering equipment available at each side of said intermediate floor, and means available at each side of said plane for conducting the tempered sand outwardly and downwardly to the molding machines. 115 120 125 130

16. A homogenizing apparatus for foundry sand which consists in a homogenizing floor, a conveyer for depositing and distributing the sand thereon, a wetting equipment, and an apparatus moving over the floor whereby the sand undergoing homogenizing is repeatedly put in motion and permitted to rest intermittently.

17. A homogenizing apparatus for reused foundry sand from the shake-out apparatus which consists, in combination, of a floor whereon the sand is distributed for cooling, exhaling, wetting, resting and conveyance, a manually controlled wetting equipment, a mechanically operated but manually controlled conveyer, and mechanism whereby it is moved over the floor at manually controlled intervals whereby the periods of rest and motion of the sand are manually determined.

18. A homogenizing apparatus for reused foundry sand comprising, in combination, a shake-out hopper, a riddle disposed below said hopper, a horizontal belt conveyer disposed below said riddle, an elongated homogenizing floor extending lengthwise of and below said belt, a plow for scraping the sand from said belt and permitting it to fall to said floor, means for moving said plow back-and-forth along the length of said belt, a series of storage bins disposed below and at one side of said floor, a wetting equipment, and a screw conveyer bodily movable lengthwise of said floor for moving the wetted sand transversely into said bins.

19. In a homogenizing apparatus for reused foundry sand, in combination, a hopper which receives the used sand from the riddle, said hopper having a lower discharge orifice, an endless belt conveyer running under and spaced slightly below said discharge orifice, means for distributing the sand upon the belt conveyer in a relatively thin layer of uniform thickness, a homogenizing floor disposed below said belt conveyer, and a plow movable lengthwise of said belt for scraping the sand therefrom and permitting it to fall to said floor in the form of a thin sheet.

20. In a homogenizing apparatus for reused foundry sand, in combination, a hopper which receives the used sand from the riddle, said hopper having a lower discharge orifice, an endless belt conveyer running under and spaced slightly below said discharge orifice, means for distributing the sand upon the belt conveyer in a relatively thin sheet, a homogenizing floor disposed below said belt conveyer, a plow moving constantly back-and-forth along the active length of said belt conveyer for scraping the sand therefrom, and means for driving said conveyer and plow at relatively differential speeds.

21. In a homogenizing apparatus for reused foundry sand, in combination, a ho-

mogenizing floor, an endless belt-conveyer extending above and lengthwise of said floor, means for depositing the used sand upon said conveyer and a movable device for scraping the sand from said conveyer and permitting it to fall to said floor.

22. In a homogenizing apparatus for reused foundry sand, in combination, a shake-out equipment including a hopper, a sand riddle stationed below said hopper, a horizontal belt-conveyer stationed below said riddle, a homogenizing floor below said belt-conveyer, and a movable device for scraping the sand from said belt-conveyer and allowing it to fall to said floor.

23. In a homogenizing apparatus for foundry sand, in combination, an homogenizing floor, means supported above said floor for depositing the used sand along the length thereof, a series of storage bins disposed below and at one side of said floor, and an apparatus movable bodily lengthwise of said floor for moving the sand widthwise of said floor and into said storage bins.

24. In a homogenizing apparatus for foundry sand, in combination, an homogenizing floor, means supported above said floor for depositing the used sand along the length thereof, a series of storage bins disposed below and at one side of said floor, a wetting equipment, and a rotary screw-conveyer mounted for bodily movement transversely of its axis and lengthwise of said floor for conveying the sand across the floor and into said bins.

25. A sand distributing apparatus for continuous foundry systems comprising, in combination, an overhead endless belt-conveyer, means whereby the used sand from the shake-out equipment is fed onto said conveyer, a plow having a blade extending at an inclination to and adjacent said belt, and means whereby said plow may be moved along the length of said belt, whereby the sand scraped from the belt may be distributed along the floor beneath.

26. Sand conveying mechanism for continuous foundry systems comprising, a sand supporting floor, a screw-conveyer, a frame in which said conveyer is journaled with its axis parallel with said floor, supporting wheels for said frame, means for propelling said frame, and means for driving said conveyer.

27. Sand conveying mechanism for continuous foundry systems comprising, a sand supporting floor, a traveling frame supported above said floor, a screw-conveyer journaled in said frame with its axis substantially parallel with said floor, means for propelling said frame and means independent of said propelling means for driving said conveyer.

28. Sand conveying mechanism for continuous foundry systems comprising, a sand

supporting floor, a traveling frame supported above said floor, a screw-conveyer journaled in said frame with its axis substantially parallel with said floor, manually controlled means for propelling said frame and manually controlled means independent of said propelling means for driving said conveyer.

29. In a foundry system, a transfer device 10 for a traveling sand conveyer comprising a pivot post, a semi-circular overhead track supported concentrically with said post, a wheeled trolley-truck adapted to run on said track, a frame supported at one end by said 15 post and suspended at another point from said truck, and a short track-way carried by said frame and adapted to support the vehicle during transfer.

30. In a foundry system, a device for 20 transferring a traveling sand conveyer from one to another of two adjacent and parallel track-ways comprising, a pivot post disposed midway between and at the end of said track-ways, a semi-circular overhead track supported concentrically with said post, a truck adapted to run on said semi-circular track, a frame supported at one end by said pivot post, said frame being suspended from said truck at a point spaced 25 from said post, and track-ways carried by and extending transversely of said frame, said track-ways being on the same side of said post and adapted to register with either of said parallel track-ways.

31. In a foundry system, a device for 35 transferring a traveling sand conveyer from one to another of two adjacent and parallel track-ways comprising, a pivot post disposed midway between and at the end of said track-ways, a semi-circular overhead 40 track supported concentrically with said post, a truck adapted to run on said semi-circular track, a frame supported at one end by said pivot post, said frame being suspended from said truck at a point spaced 45 from said post, and track-ways carried by and extending transversely of said frame, said track-ways being on the same side of said post and adapted to register with either of said parallel track-ways.

In testimony whereof, I have signed my name to this specification.

OLIVER L. DOSCH.
